(57) **CLAIM**

The ornamental design for an infrared monitoring video camera, as shown and described.

DESCRIPTION

FIG. 1 is a perspective view of an infrared monitoring video camera of the design;

FIG. 2 is a front view thereof;

FIG. 3 is a rear view thereof;

FIG. 4 is a left side view thereof;

FIG. 5 is a right side view thereof;

FIG. 6 is a top view thereof;

FIG. 7 is a bottom view thereof; and,

FIG. 8 is a perspective view showing an operational embodiment of the claimed design with a ball-type casing rotating downward at an angle, wherein the broken lines are shown for illustrative purposes only and form no part of the claimed design.
